Watson E. Coleman, Attorney

UNITED STATES PATENT OFFICE.

GUY ANTONIO DELISSIO, OF DELMONT, PENNSYLVANIA.

RAIL-JOINT.

1,386,847.

Specification of Letters Patent. Patented Aug. 9, 1921.

Application filed May 18, 1921. Serial No. 470,716.

To all whom it may concern:

Be it known that I, GUY A. DELISSIO, a citizen of the United States, residing at Delmont, in the county of Westmoreland 5 and State of Pennsylvania, have invented certain new and useful Improvements in Rail-Joints, of which the following is a specification, reference being had to the accompanying drawings.

10 This invention relates to rail joints, and has for its object to provide a rail joint which is not affected by the expansion or contraction of the rails, and wherein the means for securing the rails cannot be 15 engaged by vibration of the rails caused by cars passing thereover.

Another object is to provide a rail joint of this character wherein means for securing the rail ends to each other is carried by one 20 of the rails and is adapted to receive the end of an adjacent rail.

25 It is also an object of the invention to provide a rail joint of this character wherein a socket member is carried by one end of the rail for the reception of the end of an adjacent rail, portions of said socket being provided with inwardly projecting protuberances adapted to engage the web of the rail within the socket to firmly engage the web 30 upon tightening of the fastening means extending through the socket.

With these and other objects in view the invention consists in the improved construction and arrangement of parts to be herein- 35 after more particularly described, fully claimed and illustrated in the accompanying drawings in which:

40 Figure 1 is a perspective view of a rail joint, constructed in accordance with an embodiment of my invention,

Fig. 2 is a transverse sectional view of the structure shown in Fig. 1,

45 Fig. 3 is a fragmentary top plan view of the joint securing means, with the rail re- moved, and

Fig. 4 is a sectional view taken on the line 4-4 of Fig. 3.

Referring to the drawings, 5 designates a rail of a conventional form, the end portion 6 of said rail being provided with a socket member 7 for securing the adjacent rail thereto.

50 The socket member 7 is substantially U-shaped in cross section, the end portion 8 of said member being formed integral or otherwise permanently secured to the base and

web of the rail 5, while the end portion 9 projects beyond the end portion 6 of the rail, the extremity of said end 6 being at the intermediate portion of the socket. The 60 socket is adapted to conform to the construction of the web and base of the rail, so as to properly hold said portions of the rail disposed within the socket. It will be noted that the walls 10 of the socket member are 65 inclined toward each other, so that the upper ends 11 of said walls will be disposed beneath the tread of the rail. The inner surface 12 of each of the walls 10 is substantially concave. The purpose of this is to 70 permit the walls of the socket to be drawn toward the web upon tightening of the fastening means.

In order to permit the walls of the socket member to firmly engage the end of the rail 75 to be secured, a ridge 13 is formed on each of the walls 10, said ridge projecting from the inner surface 12 and extending longitudinally of said walls. These ridges are adapted to engage the rail at the junction of 80 the web of the rail with the base thereof, and are substantially inclined downwardly from said walls. By the concave inner surface 12 of the walls, the intermediate portions of said walls do not come in contact 85 with the web. The upper inner edge of the walls, as well as the ends 11, engage the rail and coact with the ridges 13 to prevent movement of the rail within the socket. To assist in securing the rail within the socket, 90 the bottom 14 of the socket has a ridge 15, which extends upwardly from the central portion of the socket and longitudinally thereof, said ridge being adapted to engage the lower surface of the base of the rail im- 95 mediately beneath the web of the rail.

In this way a certain amount of movement is permitted when the rail is being secured to cause binding of the socket member on the rail. The end portion 9 of the socket is 100 provided with a plurality of openings 16, the openings in one wall of the socket registering with the openings in the opposite wall of the socket and with similar openings formed in the web of the rail. Bolts or like 105 fastening means 17 are adapted to be passed through said openings so as to bind the socket member to the rail 5a.

From the foregoing it will be readily seen that this invention provides novel means of 110 securing the ends of rails, in the form of a socket, one socket being carried by one end

of each rail, the opposite end of the rail being adapted to be received in the socket member of the adjacent rail. In view of this feature, the invention may be incorporated in the conventional forms of rails now in use, as no alteration to the ends of the rails is necessary. Another important feature is that through the medium of the ridges 13 and 15 and the upper inner edge 10 of the walls 10, it is possible to bind the socket member to the end of the rail, as resistance to a great extent is eliminated, and the pressure applied to the fastening means will also serve to draw the walls into engagement with the web and base of the rail 5^a.

What is claimed is:

A rail joint of the character described em-

bodying a rail having a socket member formed on one end thereof, said socket member being open at one end and its top, the inner walls of said socket member being substantially concave, the top and inner edges of said walls being adapted to engage the rail, ridges projecting from the walls of said socket at the junction of the web of the rail with the base of the rail, a ridge projecting from the intermediate portion of the bottom of the socket for engagement with the base of the rail, and means for urging said ridges, the top and inner edges of the walls into binding engagement with the rail end within the socket.

In testimony whereof I hereunto affix my signature.

GUY ANTONIO DELISSIO.
